UNITED STATES PATENT OFFICE.

FRANK H. LA PIERRE, OF EAST ORANGE, NEW JERSEY.

DESIGN FOR A HAIR-BRUSH.

SPECIFICATION forming part of Design No. 28,683, dated May 24, 1898.

Application filed April 21, 1898. Serial No. 678,397. Term of patent 7 years.

To all whom it may concern:

Be it known that I, FRANK H. LA PIERRE, a citizen of the United States, residing at East Orange, in the county of Essex and State of New Jersey, have invented and produced a new and original Design for a Hair-Brush; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan view of a hair-brush of my new design. Fig. 2 is a sectional view taken on line *x* of Fig. 1.

As shown in the drawings, the leading or material feature of my newly-designed hair-brush consists in the "polka-dot" ornamentation distributed over a plain ground.

In said drawings, *a* indicates the body of the brush, which is approximately oval in

general plan at the front, the outlines converging near the center, as at *b b*, and again 25 diverging at the handle, the handle being also approximately oval in outline.

The back face of the brush-body is centrally plain, as indicated in Fig. 2, with convexly-rounded edges *c*. The plain surface of 30 the back is ornamented with "polka-dots" *d*, distributed widely apart over said surface, and on the enlargement of the handle is displayed a dot *e* of larger superficial proportions.

Having thus described my invention, what I claim as new is—

The design for a hair-brush as herein shown and described.

In testimony that I claim the foregoing I 40 have hereunto set my hand this 18th day of March, 1898.

FRANK H. LA PIERRE.
